UNITED STATES PATENT OFFICE

2,501,116

LIQUID FUEL STOVE FOR CURING TOBACCO

Norwood C. White and Hubert M. Dickens,
Whiteville, N. C.

Application April 8, 1947, Serial No. 740,082

1 Claim. (Cl. 126—93)

1
This invention relates to a liquified gas burning tobacco curer.

An object of the invention is to provide a tobacco curer of this character, which is easy to operate, safe to use and since only vapors are burnt at the curer, no liquid reaches the burner, thus making the burners instantly adjustable as to the heat produced. With a non-varying flame, higher temperatures are produced in the barn, making a more efficient operation of curing the tobacco.

With the above and other objects and advantages in view, the invention consists of the novel details of construction, arrangement and combination of parts more fully hereinafter described, claimed and illustrated in the accompanying drawings in which:

Figure 1 is a side elevational view of an embodiment of the invention;

Figure 2 is an end elevational view;

Figure 3 is a vertical sectional view on the line 3—3 of the Figure 1;

Figure 4 is a longitudinal sectional view of Figure 1;

Figure 5 is a cross-sectional view on the line 5—5 of Figure 4;

Figure 6 is a sectional view of the control valve in half open position and

Figure 7 is a sectional view of the control valve in full open position.

Referring more in detail to the drawings, the tobacco curer embodying the invention is designated generally by the reference numeral 10, and comprises the end pieces 11 and 12 respectively, which are bent in a substantially U-shaped form to provide oppositely disposed side flanges 13 and 13' on end 11, and 14 and 14' on end 12. The forward edges of flanges 13 and 13' are provided with outwardly extending right angular flanges 15 and 15' while the forward edge of flanges 14 and 14' are provided with similar flanges 16 and 16'. The upper and lower ends of the flanges 13 and 13' are provided with outwardly extending right angular flanges 17 and 17', while the upper and lower ends of flanges 14 and 14' are provided with similar flanges 18 and 18', and the upper and lower ends of the end pieces 11 and 12 are provided with outwardly extending right angular flanges 19 and 19' respectively.

The upper ends of the end pieces have secured thereto, on the inner sides of the flanges 13 and 13', and 14 and 14', by welding or the like, the side plates 20 and 20' respectively, and these plates have longitudinal inwardly extending right

angular flanges 21 and 21' respectively, while at the lower ends, the end pieces have the downwardly curved baffle plate or windshield 22 secured thereto by means of the upstanding flanges 23 and 23' respectively. Extending longitudinally of the baffle plate 22, along the medial line thereof, is the elongated slot 24 to furnish air to the tubular burner 25 which is capped at each end by caps 26 and provided with a plurality of burner apertures 27. The burner 25 is supported longitudinally of the curer by means of brackets 28 and 28' respectively, which are provided with end flanges 29 and 29' respectively, which are secured by welding or the like to the side flanges 13 and 13' and 14 and 14'.

Interposed in the center of the burner 25 is a control valve 30 which is connected by a pipe 31 to a fuel supply, not shown. The valve 30 is provided with ports 32, 33 and 34 respectively, so that, as shown in Figure 6, port 33 will communicate with one-half of the burner 25, and with the supply pipe 31, so that only one-half of the burner is in use. In Figure 7, with ports 32 and 34 communicating with the burner, and port 33 with pipe 31, the entire burner is in use. The reverse of Figure 6 is also apparent, since if port 34 is in communication with pipe 31, port 33 will be in communication with the opposite half of the burner 25.

30 A heat spreader 35, which is substantially formed and shaped as the conventional peaked roof, is provided with vertical depending arms 36, which are provided in pairs at each end of the curer so that they can be secured to the end pieces 11 and 12 by fasteners 37, and the heat spreader can be made adjustable as desired by providing a plurality of openings to receive the fasteners 37.

Secured to the inner surface of the heat spreader 35 is a substantially triangular shaped baffle 38 providing a partial dead air space 39 between the spreader and the baffle, which prevents the discoloration of the tobacco during the curing thereof. Longitudinal cutouts 40 along the longitudinal edges of the baffle provide the feet 41 whereby the baffle is secured by welding to the spreader 35 below the inturned upper flanged ends 42 of the arms 36. The cutouts intermediate of the feet 41 form a slight air space which permits a slight circulation of air into the space 39. Thus there is enough air seeping into the space 39 to reduce the temperature of the heat spreader sufficiently to prevent an excess of heat directly over the heating unit.

50 An excess temperature would cause a setting of

the green color in the tips of the tobacco leaves hanging over the unit before the curing process has progressed far enough for the tobacco to reach the desired color.

The curer is made of sheet metal throughout, which may be rust-proofed or galvanized, and any number of these units may be used in the barn as desired.

There has thus been provided a tobacco curer which, it is believed, will accomplish the objects of the invention, and it is believed that from the foregoing description, the construction and operation of the invention will be apparent to those skilled in the art.

It is also to be understood that changes in the minor details of construction, arrangement and combination of parts may be resorted to, provided they fall within the spirit of the invention and the scope of the appended claim.

Having thus described the invention, what is claimed as new and desired to be secured by Letters Patent is:

A tobacco curer heater comprising a rectangular shaped casing having side and end walls with the end walls having extended webs at the sides providing channel shaped supporting elements for said side walls, said side walls each having a longitudinally extending opening in the lower part thereof, a centrally positioned perforated pipe extended longitudinally through the lower part of the casing providing a burner

header, a three-way valve positioned in the center of the said burner header and having a fuel supply pipe extended therefrom, a baffle carried by the extended ends of the end walls spaced below the header and extended upwardly from a point below the header to the said extensions of the end wall, said baffle having a longitudinally disposed opening therein positioned below the header, a superimposed hood triangular shaped in cross section and having inclined side and end walls spaced above the upper end of the casing, depending arms positioned in the ends of the hood and extended downwardly into the casing supporting the hood above the casing, and an inner baffle positioned midway of the height of the hood extended from wall to wall of the hood providing a partial dead air space within the hood.
